1.2 : Back

1.3 : Left

1.4 : Right

1.5 : Top

1.6 : Bottom

1.7 : Cross sectional

1.8 : Perspective

1.9 : Perspective

An inner wall surface on the out-course side of a flow channel in an inlet pipe body portion is curved from an inlet port to an outlet pipe body portion. A part of an outer wall surface on the in-course side of the flow channel in the inlet pipe body portion protrudes outward in a curved shape while the inner wall surface is depressed outward. A valve stem is positioned on a bias toward the outlet pipe body section from the center of the inlet port in the bottom view.
